UNITED STATES PATENT OFFICE.

JOHN G. GARRETSON, OF SALEM, IOWA.

IMPROVEMENT IN PUMPS.

Specification forming part of Letters Patent No. 41,291, dated January 19, 1864.

To all whom it may concern:

Be it known that I, JOHN G. GARRETSON, of Salem, in the county of Henry and State of Iowa, have invented a new and useful Improvement in Force-Pumps; and I do hereby declare that the following is a full and exact description thereof, reference being had to the accompanying drawings and the letters of reference marked thereon, in which—

Figure 1 is a vertical elevation and outside view of the whole pump ready for use, with a wooden stem, K, as a support to the handle, which is now supposed to be descending. Fig. 2 is a longitudinal sectional view showing the plunger within the cylinder and the partition marked *e* dividing the tube *c* in two equal parts. The position here shown is that of the downward movement of the handle and ascent of the plunger. Fig. 3 is the same view precisely, only the handle is supposed to be lifted, and thereby forcing the pipe D to the opposite side of the pipe C to receive the water from below the plunger.

The peculiarity of my invention consists in making that part of the tube *c* entering into the cylinder and connecting with the plunger B double—that is, divided longitudinally into two equal parts by the partition *e* terminating at *g*, while the pipe D is a single tube and reaches to the top of the well, or where you wish to discharge the water, and then by a device somewhat like a parallel rule, which I call the “joint,” when operated on by the handle through the pipe D changes the position of the single pipe D over and upon the double pipe C alternately from one side to the other just at the time that, by the ascent or descent of the plunger, the water is forced up that side of the pipe, while the other is left open to receive the water, the currents of which are clearly indicated by the arrows, as seen in Figs. 2 and 3.

To enable others skilled in the art to make and use my pump, I will more particularly describe the same, referring to the drawings and the letters thereon.

A, Fig. 1, is the cylinder or pump-barrel—say four inches in diameter and seven or eight inches long—as adapted to wells twenty-five or thirty feet deep, made of iron, brass, or other suitable material, and when put together has only one opening, and that is where the

tube *c*, Fig. 2, enters, on the lower end of which is seen the plunger B, Figs. 2 and 3, and at the upper end, and attached to the tube *c*, is seen *g*, shown at an angle of about fifteen degrees with the tube. The use of this is only to form a pivot to the links *i i*, which may be about one and three-fourths inch long from center to center. The other end of these links is pivoted at *f*, which is firmly connected with the pipe D, extending to the top of the well, where it is fastened to the handle H, Fig. 1. To make the pipe D, you may use common three-fourths-inch gas-pipe. Thus, by drawing down the handle you draw up the pipe D and strain on the links *i i*, and bring *f* and *g* as nearly in a direct line from the cylinder to the top of the well as it can, for the lower end of the pipe D coming in contact with the upper end of the pipe C and the partition *e* on the highest side, thus forming a continuous tube from the plunger B to the top of the well, the water now passing out of the upper part of the cylinder in the direction indicated by the arrows. Then by lifting up the handle the pressure falls on the links *i i* and brings *f* and *g* as near together as they can come until the pipe D is arrested in its further lateral progress by coming in contact with the other side of the pipe C and partition *e*, as will be better seen in the position of Fig. 3, thus forming a continuous tube from the plunger B to the top of the well. Thus alternately bearing down and lifting the handle, you change the pipe D from side to side, and always to that side next to discharge its water, and so bring the water up in almost direct lines, without quirks or short turns, and completely dispensing with anything like valve or cut-off, and forming a double-acting force-pump yielding a nearly or quite continuous stream of water while in action, but when left at rest immediately lets all its water descend to a common level, that being useful in summer to keep the water cool, and in winter to prevent its freezing. This pump, being a force-pump, must be immersed in the water, and as it receives its water from the top is not likely to be obstructed by gravel or mud being drawn into the cylinder.

I contemplate using my pump in all situations where water is to be brought from a lower to a higher level of any height, having

due reference to the well-known laws of hydraulics in adapting the diameter of the cylinder and length of the stroke to the height the water has to be raised. I also propose adapting my invention to fire-engines.

What I claim as my invention, and desire to secure by Letters Patent, is—

The joint formed by the parts *f* and *g* with the links *i i*, Fig. 1, in the position shown in the drawings when acted on by the handle *H*, Fig. 1, and made to move the pipe *D* alter-

nately from side to side of the pipe *C*, and with the partition *e*, forming a continuous tube for conducting the water from the bottom of the cylinder to the top of the well, making a double-acting force-pump without valve or cut-off.

JOHN G. GARRETSON.
